[57] **ABSTRACT**

A new variety of Streptocarpus plant is characterized
by its purplish blue flower having dark violet striping in
the throat. It has large flowers, long permanence and is
generally nonfertile.

1 Drawing Figure

1

BACKGROUND OF THE NEW PLANT

The present invention comprises a new and distinct
cultivar of *Streptocarpus x hybridus* known by the vari-
etal name Greta, formerly named Helle Glocke. The 5
new cultivar is an irradiated sport of Nadia whereas
Nadia is a cross between the seed parent Wiesmoor Blue
and the pollen parent Constant Nymph.

The new cultivar is basically the same color as Nadia
and has the same shape of bloom. However, the new 10
cultivar has more blooms per plant and the blooms last
substantially longer than for Nadia.

The new cultivar was discovered in 1975 in Vaih-
ingen, Federal Republic of Germany; was first asexually
reproduced by cuttings in Vaihingen, Federal Republic 15
of Germany; and has been repeatedly asexually repro-
duced by cuttings at Oglevee Floral Company in Con-
nellsville, Pa. It has been found to retain its distinctive
characteristics through successive propagations.

The new cultivar, when grown in a greenhouse in 20
Connellsville, Pa., has a response time of eight weeks
from a plantlet (a well rooted young plant in a five
centimeter pot) to a flowering plant in a ten centimeter
pot.

DESCRIPTION OF THE DRAWING

The accompanying drawing illustrates the new culti-
var, the color being as nearly true as possible with color
illustrations of this type.

BACKGROUND OF THE NEW PLANT

The following detailed description sets forth the
characteristics of the new cultivar. The data which
defines these characteristics were collected from asex-
ual reproductions carried out by the Oglevee Floral 35
Company in Connellsville, Pa. The plant history was
taken on eight week plants blossomed under natural
light in a greenhouse and color readings were taken
indoors under 100 foot candles of cool white fluores-
cent light. Color references are primarily to the R.H.S. 40
color chart of the Royal Horticultural Society of Lon-
don. Some color reference is to Exotica III and such
reference is duly noted.

Botanical classification: Gesneriaceae (family); *Strep-*
tocarpus x hybridus (genus x species).

2

Flower:

Fully expanded.—Six centimeters.

Borne.—In clusters of one to six flowers per flower
stalk above the foliage. Flower stalks arise from
mid-rib of each leaf.

Stems.—Single, long and pubescent.

Form.—Funnel formed in an umbel.

Permanence.—Long lasting 21 to 25 days.

Color:

Front of petals.—Fan 2 violet group 88-A.

Throat.—Fan 1 yellow group 3-B with a plurality
of stripes, Fan 2 violet group 83-A, extending
into the center of the petals.

Base of petals.—Fan 2 purple group 76-D.

Reverse of petals.—Fan 2 violet group 88-C.

Tonality from a distance.—Purplish blue and dark
violet striping in throat (Exotica III).

Discoloration.—Insignificant.

Petals:

Texture.—Velvet.

Appearance.—Individually lobed and smooth mar-
gin.

Arrangement.—Regularly united into an elliptical
form.

Persistance.—Lives for 21 to 25 days and remains
on plant in dry form until picked.

Fragrance.—None.

Reproductive organs:

Anthers.—Two per flower and interconnected.

Filament.—Two and one-half centimeters initiating
from the base of petal and extending to the an-
ther.

Pollen.—Generally nonfertile.

Style.—Extends from tip of ovary one centimeter
and terminates in a flattened stigma.

Ovaries.—Long and narrow, one and one-half milli-
meters in diameter and one and one-half centime-
ters long.

Plant:

Form.—Leaves rosulate from a crown at the soil
line.

Growth.—A spreading, free flowing habit with leaf
bases being acute.

Height from soil line.—15 to 20 centimeters.

Spread.—35 to 40 centimeters.

Foliation:

Plant 4,522

3

Top side.—Fan 3 green group 137-B.

Size.—Approximately 20 centimeters in length and 5 to 10 centimeters in width at widest point.

Quantity.—10 to 15 leaves.

Shape.—Oblanceolate.

Ribs and veins.—Pinnate.

Rib and vein color.—Fan 3 green group 138-B.

4

Margin.—Ruffled margin with crenate serrations.

Underside.—Fan 4 greyed green group 193-A.

Stipules.—None.

5 I claim:

1. A new and distinct variety of *Streptocarpus* substantially as herein shown and described.
